UNITED STATES PATENT OFFICE.

ORVILLE COOLEY, OF BATAVIA, NEW YORK, ASSIGNOR TO THE JOHNSTON HARVESTER COMPANY, OF SAME PLACE.

GRAIN-BINDER.

SPECIFICATION forming part of Letters Patent No. 321,692, dated July 7, 1885.

Application filed April 16, 1884. (No model.)

To all whom it may concern:

Be it known that I, ORVILLE COOLEY, a citizen of the United States, residing at Batavia, in the county of Genesee and State of New York, have invented a new and useful Improvement in Grain-Binders, of which the following is a specification.

My invention relates to improvements in grain-binders in which a reciprocating twine-carrying needle is used in conjunction with the other mechanism usually employed for the purpose of binding grain; and the objects of my improvements are, first, to provide a tucking device placed wholly upon the upper side of the breast-plate and operated upon directly by the needle-arm; second, to arrange for the successful operation of the tucker, giving it a positive movement, even if its actuating-spring should become inoperative; and, third, to afford means for preventing the entanglement of the twine carried by the needle, and still assure the operation of the tucker at each forward movement of the needle and have the parts at all times work in unison and in such manner that the springing or yielding of the needle will not act deleteriously in the tying of the knot.

I attain these objects by the mechanism illustrated in the accompanying drawings, in which Figure 1 is a plan view of the breast-plate with the needle in position ready to act upon the tucking-operating mechanism in its forward thrust. Fig. 2 is a side elevation of the needle as it has reached the extent of its throw and just at the point of receding; and Fig. 3 is a perspective view taken from the side upon which the tucker is pivoted, with the needle at the point when the tucker first comes in contact with the twine.

Similar letters refer to similar parts in the several views.

A is the breast-plate having the slot a, and upon which is mounted the tucker B and the tucker-operating lever B'. Upon the free end of this lever B' is pivoted the friction-roller b.

C is a stud, which pivotally secures the tucker to the breast-plate, and around which is coiled the spiral spring c. This stud is made fast to the breast-plate, with the end of the

coil secured to the head of the stud, so that 50 the spring-coil is compressed when in practical operation.

c' is a lug placed upon the tucker about midway between the pivotal connection and the point. To this stud c' is secured the reverse 55 end of the spring in such manner that it is compressed in the downward throw of the tucker and causes the tucker to return to the position shown in Fig. 1 upon the backward movement of the needle.

The point of the tucker is made slightly 60 hooking upon its lower edge, so as to catch and hold the binding-twine and not allow it to slide over the end while being carried to the knotting device. The rear end of the tucker 65 extends outward and past the edge of the breast-plate, for a purpose hereinafter described.

D represents an arm of the bundle-discharger, the operating mechanism of which is not 70 shown; and as I claim nothing upon the machinery for operating the needle, knotting device, &c., it will not be necessary for me to describe the working of the said parts further than is required for the conjunctive action 75 with my tucking device.

It will be observed that the tucker-lever is slotted, as at e, through which passes the headed bolt e', and by which the lever is held in close proximity with the breast-plate, and yet 80 allow of the necessary swing from the pivotal connection e'. In order that the roller upon the lever may be brought into peripheral contact with the needle-arm, as well as to overlap the tucker-point, it is made of greater 85 diameter than the lateral face of the lever at the place where the roller is pivoted.

It will be observed that the entire tucking mechanism is located upon the upper side of the breast-plate, thus obviating the necessity 90 of a shield to serve as a preventive against the accumulation of straws or other deleterious matter at this point to interfere with the practical working of the machine.

In the practical operation of my tucking device the grain to be bound is, by suitable mechanism, placed upon the table located underneath the breast-plate, and when a suffi-

cient quantity is gathered to form a bundle the needle is automatically brought forward upon the arc of a circle, of which the end of the arm is the center, so as to carry the twine 5 around the gavel. In the forward movement the needle-arm comes in contact with the roller which lies in the path of the needle, and causes the lever to swing upon the pivotal point, and in so doing it impinges against the 10 rounded end of the tucker, causing it to swing across the slot *a*, so as to come in contact with the needle in its forward movement and bring the binding-twine in contact with the knotting device, whereby the knot is tied, and (by 15 suitable mechanism) the bundle is discharged.

The purpose of the heel-extension to the tucker will now be explained. It will be seen that when the tucker is in the position shown in Fig. 3 the rear part extends past the bed- 20 plate, and were it to remain in this position until the revolution of the bundle-discharger the arm would strike this extended heel, and by so doing bring the tucker back to its nor-

mal position ready for another operation, so that should the spring become inoperative 25 the bundle will still be discharged in a bound condition without the aid of the spring; yet I prefer using the spring, for in so doing the tucker plays freely with but little friction, and the operation is rendered doubly secure. 30

I am aware that prior to my invention tuckers have been made having a positive movement. Therefore I do not claim such a movement, broadly; but

What I do claim as my invention, and desire to secure by Letters Patent, is— 35

The combination of the needle, the tucker, the tucker-securing bolt upon which it turns, and the bundle-discharging arm made to act directly upon the rear extension of the tucker, 40 substantially as herein described.

ORVILLE COOLEY.
